T. E. KANE.

MACHINE FOR TRIMMING THE OVERFLOW FROM THE BREAST OF RUBBER HEELS.
APPLICATION FILED JAN. 19, 1920.

1,376,018.

Patented Apr. 26, 1921.

FIG. 1.

FIG. 2.

Inventor:

Thomas E. Kane,

By his attorney, Parker N. Goodwin.

UNITED STATES PATENT OFFICE.

THOMAS E. KANE, OF CANTON, MASSACHUSETTS, ASSIGNOR OF ONE-HALF TO
ABRAHAM SYDEMAN, OF BOSTON, MASSACHUSETTS.

MACHINE FOR TRIMMING THE OVERFLOW FROM THE BREAST OF RUBBER HEELS.

1,376,018.

Specification of Letters Patent. Patented Apr. 26, 1921.

Application filed January 19, 1920. Serial No. 352,291.

To all whom it may concern:

Be it known that I, THOMAS E. KANE, a subject of King George V of England, residing at Canton, in the county of Norfolk and State of Massachusetts, have invented new and useful Improvements in Machines for Trimming the Overflow from the Breast of Rubber Heels, of which the following is a specification.

10 This invention relates to a machine for trimming the overflow from the breast of rubber heels: Rubber heels when molded have a thin fin of rubber extending around the entire upper edge of the heel and that portion of the fin which extends along the upper edge of the breast of the heel is known as the overflow from the breast and will be so referred to in the following specification. It has been the custom to trim 15 this thin fin of rubber from the upper edge of rubber heels, all except the overflow from the breast by means of a pair of rotary cutters and this was possible because the periphery of the heel, except the breast portion, is formed on a convex curve and the outer edge of the heel as a whole is inclined or tapers inwardly from the upper edge toward the tread of the heel, but the breast of the heel is substantially vertical or at right 20 angles to the tread of the heel and moreover it is concave and therefore it has been heretofore impossible with the machines on the market to trim the overflow from the breast by means of rotary cutters. This work of 25 trimming the overflow from the breast is at present being done by hand by means of shears and when so done the work is often-times imperfect and unsatisfactory and to do the work carefully requires the expenditure of considerable time by skilled labor.

With my invention all of the work can be done by a pair of rotary cutters, and to enable this to be done I use preferably a pair of rotary cutters, the lower of which is preferably substantially greater in diameter than the upper cutter, and adjacent to the peripheries of said cutters at the cutting point I provide a convexly curved work-support upon which the work rests, the upper face thereof being inclined at an angle to the median axial lines of the cutters.

In the preferred embodiment of my invention I utilize a pair of rotary cutters and adjacent thereto a work-support having its work contacting face inclined downwardly

at an angle, said work-support being preferably convexly curved transversely of the median axial lines of the cutters.

This invention consists in the combination and arrangement of parts set forth in the following specification and particularly pointed out in the claims thereof.

Referring to the drawings:

Figure 1 is a front elevation partly in section of my improved machine for trimming rubber heels, a heel being shown in section in position for trimming the overflow from the breast.

Fig. 2 is a detail end elevation of the cutters and work-support, a heel being shown dotted in two positions.

Like numerals refer to like parts throughout the several views of the drawings.

In the drawings, Figs. 1 and 2, 5 is the frame of the machine; 6 and 7 are rotary shafts to which are fastened rotary cutters 8 and 9, respectively. The shafts 6 and 7 are rotated by means of pulleys 10 and 11 and are rotatably mounted upon bearings 12 and 13 on the frame of the machine and are 75 adjustable longitudinally by means of screws 14 and 15, being locked in position by means of lock nuts 16 and 17.

A work-support 18 is fastened to a plate 19 which is fastened to the base 20 of the frame 5. Said work-support is convexly curved and is provided with a work-supporting face 21 which is inclined downwardly from the adjacent peripheries of the cutters 8 and 9, the work-supporting face of the work-support thus being inclined at an angle to the median axial lines of the shafts 6 and 7. It will be noted that the diameter of the cutter 8 is substantially smaller than the diameter of the cutter 9.

90 The general operation of the machine is as follows:

Referring to Figs. 1 and 2, rotary motion is imparted to the shafts 6 and 7, whereby a rotary motion is imparted to the cutters 8 and 9. When trimming the overflow from the breast of the heel, said heel is held in the position illustrated in Fig. 1, in which the heel 22 is placed with the breast 23 thereof resting upon the work-supporting face 21 of the work-support 18, and the operator moves the heel from the position shown in dotted lines, Fig. 2, at the left of the cutters as viewed in said figure to the position shown in dotted lines at the right of said cutters.

- Thus the overflow 24 from the breast of said heel 22 which projects from the upper edge thereof is trimmed quickly and neatly by passing between the cutters 8 and 9.
- 5 While I have described my invention as particularly adapted to trimming the overflow from the breast of rubber heels, it is to be understood that I do not confine my invention to this work only, as it is evident 10 that the same mechanism hereinbefore described may be utilized for trimming other articles than rubber heels wherein a thin fin projects from a concave edge.
- Having thus described my invention, what 15 I claim and desire to secure by Letters Patent is:
1. A machine for trimming the overflow from the breast of rubber heels having, in combination, a pair of rotary cutters and a work support having a work-supporting face adjacent to the periphery of said cutters and inclined longitudinally thereof to the median axial lines of said cutters.
  2. A machine for trimming the overflow 25 from the breast of rubber heels having, in combination, a pair of rotary cutters arranged one above the other, the upper of said cutters being of substantially smaller diameter than the lower one of said cutters
- and a work-support arranged adjacent to 30 said cutters, the work-supporting face of said work-support being inclined downwardly from a point adjacent to said cutters and longitudinally of the median axial lines of said cutters.
3. A machine for trimming the overflow from the breast of rubber heels having, in combination, a pair of rotary cutters and a convexly curved work-support adjacent to 40 said cutters and having its work-supporting face inclined downwardly away from the peripheries of said cutters and at an angle to the median axial lines of said cutters.
4. A machine for trimming the overflow from the breast of rubber heels having, in combination, a rotary cutter and a convexly curved work-support adjacent the periphery of said rotary cutter, the work-supporting face of said work-support being inclined to 45 the median axial line of said cutter.
- 50 In testimony whereof I have hereunto set my hand in presence of two subscribing witnesses.

THOMAS E. KANE.
